MAGAZINE BASKET

Clifford W. Fraley, Youngstown, Ohio

Application May 8, 1953, Serial No. 24,928

Term of patent 14 years

(Cl. D33—2)

To all whom it may concern:

Be it known that I, Clifford W. Fraley, a citizen of the United States, residing at Youngstown, in the county of Mahoning and State of Ohio, have invented a new, original, and ornamental Design for a Magazine Basket, of which the following is a specification, reference being had to the accompanying drawing forming a part thereof.

The figure is a perspective view of a magazine basket, showing my new design.

The undisclosed end and side are substantially like the end and side shown.

I claim:

The ornamental design for a magazine basket, as shown and described.

CLIFFORD W. FRALEY.
